UNITED STATES PATENT OFFICE

HARRY R. PRIEST, OF LOUDONVILLE, OHIO

TOOTH CLEANING AND POLISHING TOOL

Application filed July 15, 1930. Serial No. 468,131.

This invention relates to tooth cleaning and polishing tools and has for an object to provide a tool capable of withstanding great pressure whereby stains, tartar and other accumulations may be effectively removed from the teeth, the tool having a reversible cap which when applied to one end of the tool forms a grip whereby great leverage may be exerted upon the tool, and when applied to the opposite end, the cap serves as a housing to protect the cleaning and polishing tuft element from contamination.

A further object of the invention is to provide a tooth cleaning and polishing tool in which the shank of the tool is provided with a goose neck contiguous to the cleaning and polishing tuft element to comfortably receive the lips while the tuft element is being manipulated at various angular positions to operate on the fronts, backs, and edges of the teeth from the gums to the biting edges thereof, said shank having a recess at one end to receive a supply of dental floss a separate cap being provided in addition to the usual cap which closes said recess and carries the dental floss cutter, said additional cap being adapted to form a housing to protect the projecting end of the dental floss from contamination.

A still further object of the invention is to provide a tooth cleaning and polishing tool having the reversible cap provided with a mirror and having also an additional cap detachably secured to the reversible cap and also carrying a mirror, the two mirrors providing means for thoroughly inspecting the teeth, since said cap mirror may be held in the mouth on the tongue and the mirror of the reversible cap, which, as above stated is also a grip, may be held outside the face to reflect the image from the mirror in the mouth so that the backs of both the upper and lower teeth may be conveniently inspected.

With the above and other objects in view the invention consists in certain novel details of construction and combinations of parts hereinafter fully described and claimed it being understood that various modifications may be resorted to within the

scope of the appended claims without departing from the spirit or sacrificing any of the advantages of the invention.

In the accompanying drawings forming part of this specification,

Figure 1 is a perspective view of the tooth cleaning and polishing tool in operative position,

Fig. 2 is a longitudinal sectional view through the cleaning and polishing tool in the position shown in Fig. 1,

Fig. 3 is a longitudinal sectional view through the tool with the reversible cap forming a housing for the cleaning and polishing tuft element and showing the separate cap housing the dental floss projecting end, and

Fig. 4 is a greatly enlarged detail view showing a conical shaped cleaning and polishing tuft element.

Referring now to the drawings in which like characters of reference designate similar parts in the various views, 10 designates a substantially cylindrical shank which is provided near one end preferably with a pair of screw threaded surfaces 11 and 12 adapted to selectively receive a hollow reversible cap 13. The cap is interiorly threaded, as shown at 14, near one end to engage the above mentioned screw threads 11 and 12.

The shank 10 is cut away laterally, as shown at 15, to provide a goose neck and terminates contiguous to the goose neck in a relatively short annular head 16, the surfaces of which are rounded, as shown at 17 and 18. The head extends substantially at a right angle to the axis of the shank and is so constructed as to extend in length to approximately the extended axis or center line of the shank 10.

A cleaning and polishing element is removably carried in the head and comprises a socket 19 which is provided with a reduced threaded stem 20 adapted to screw into the head which is threaded to receive the stem. A single unitary comparatively rigid tuft 21 of bristles, preferably badger or boar bristles, is rubber set or embedded in a hard rubber base 22 which latter is driven snugly

into the socket 19 so as to form an integral unitary structure therewith.

The shank is provided with an axial recess 22 which forms a magazine to receive a supply of dental floss 23. The shank is uniformly reduced exteriorly and threaded to receive a cap 24 which closes the end of the dental floss magazine, the cap having an axial opening 25 through which the end 26 of the dental floss projects so as to be easily grasped for measuring off a desired length of the material. A spur 27 is struck from the metal of the cap and forms a cutter so that a desired length of the dental floss may be cut off.

The above mentioned reversible cap 13, when screwed onto the threads 11 of the shank forms a grip by means of which great pressure may be applied to the shank for causing the tuft 21 to scour off stains, tartar and other accumulations from the teeth. By means of the grip great leverage can be exerted to apply pressure up to and exceeding 20 pounds, which great pressure is necessary, as is well known to those skilled in the art of dentistry, to remove disfiguring discolorations and accumulations from the teeth and expose the natural polish and luster thereof.

30 The cap 13 is provided in the closed end 28 with a mirror 29 and preferably an additional cap 30 is screwed onto the exterior of the reversible cap or grip 13, as shown at 31, and this additional cap is also equipped 35 with a mirror 32. The cap 30 may be held in the mouth on the tongue to reflect the images of the backs of the upper and lower teeth from the mirror 32 onto the mirror 29 of the grip 13, which latter may be held 40 outside the face in proper position to view the reflected image from the mirror 32.

By referring to Fig. 3, it will be seen that the reversible cap 13 may be applied to the screw threads 12 in which position the cap 25 forms a housing for the cleaning and polishing tuft 21 to prevent contamination thereof.

When the reversible cap 13 is in position to form a housing, it is desirable also to have 50 the projecting end 26 of the dental floss protected from contamination and for this purpose a cap 33 is provided, preferably the cap being provided with internal screw threads to engage the screw threads of the cap 24.

In Fig. 4 is shown a modified form of the cleaning and polishing element, the same comprising a socket 35 which is provided with a threaded stem 36. A substantially 60 conical tuft 37 of relatively stiff bristles is rubber set or embedded preferably in a hard rubber base, as above described, and driven into the socket so as to become integrally associated therewith. Various other contours of tufts may be employed to accommo-

date the device to various conditions of service.

It will be noted that by virtue of the goose neck 15 in the shank the tool may be manipulated between the lips without injury to the latter, while by virtue of the cleaning and polishing tuft 21 projecting at substantially a right angle to the axis of the shank 10, the tool may be manipulated in various angular positions to scour the fronts and backs of the teeth as well as the crevices therebetween to thoroughly remove accumulations therefrom.

It will be here stated that the tool above described is capable of withstanding great pressure, since the bristles in the tuft 21 are so compactly assembled and are of such short length as to resist lateral spreading, such as is found in the use of ordinary tooth brushes when pressure is applied thereto. It is well known that ordinary tooth brushes are only capable of withstanding a pressure up to about 12 pounds when both the bristle component and the handle component become entirely ineffective, due to spreading apart of the bristles and in some cases breaking of the handles.

While ordinary tooth brushes cease to function under pressures exceeding 12 pounds, and therefore are entirely inadequate to remove stains and tartar which require great pressure, my improved device, it will be observed, is designed primarily to accomplish the removal of stains and tartar and therefore is capable of withstanding the great pressures which must be used to expose the true luster and polish of the teeth.

It will be pointed out that when the reversible cap 13 is engaged selectively with either of the two sets of screw threads 11 or 12, it will extend in prolongation of the axis of the grip 10, as best shown in Figs. 2 and 3. It will be further pointed out that when the additional cap 33 is applied, this cap coacts with the reversible cap 13 in forming a complete housing so that the cleaning and polishing bristle tuft 21 as well as the projecting end 26 of the dental floss are both completely housed and protected against contamination when the device is not in use.

For ventilating the cleaning and polishing element orifices 38 are formed in the wall of the reversible cap 13 near the major end thereof, in the present embodiment of the invention the cap being frusto-conical in contour to provide a comfortable large grip when used as such. The mirror 29 being in the butt end of the reversible cap is of sufficient diameter to be very effective in use.

Having thus described the invention, I claim:

1. A tooth cleaning and polishing tool comprising a shank terminating at one end in a goose neck, a hollow head offset from

the goose neck to extend at substantially a right angle to the axis of the shank and of sufficient length to extend approximately to said axis, a cleaning and polishing element 5 detachably secured in said head, a dental floss magazine in the shank opposite said head, and a reversible cap adapted to form either a grip to extend in prolongation of said shank and house said magazine or a 10 housing to house said cleaning and polishing element.

2. A cleaning and polishing tool comprising a shank having a dental floss magazine in one end, a cleaning and polishing element 15 disposed at the opposite end of said shank, said shank being provided exteriorly of said magazine with sets of screw threads, and a detachable cap adapted to engage one set of said screw threads and extend in prolongation of said shank to house said magazine and form a grip for applying pressure to said cleaning and polishing element and being adapted to be reversed to engage the other set of screw threads and surround and 20 prevent contamination of said cleaning and polishing element.

3. A cleaning and polishing tool comprising a shank having an axial recess for the storage of dental floss, a cap forming a 30 closure for said recess and provided with an opening to permit the end of the dental floss to project therethrough, said cap having a cutter for cutting off a desired length of said dental floss, a cleaning and polishing element on said shank remote from said recess, said shank being threaded exteriorly at spaced points adjacent to said recess, and a reversible cap adapted to engage one set of said screw threads and extend in prolongation of said shank to form a grip therefor, said cap being adapted to be reversed and engage the other set of screw threads and when in this position forming a housing to protect said cleaning and polishing element from contamination, said cap when positioned to form a grip concealing the first named cap for the dental floss recess and protecting the dental floss from contamination.

4. A cleaning and polishing tool comprising a shank, a cleaning and polishing element removably attached to one end thereof and extending at substantially a right angle to the axis of said shank, there being an axial recess formed in said shank at the opposite end thereof from said element and adapted to receive dental floss, said shank being exteriorly threaded at spaced points adjacent to said recess, a cap adapted to house the end of said dental floss, and a reversible cap having screw threads adapted to engage one of said threaded portions of said shank and form a housing over said cleaning and polishing element, said reversible cap being adapted to be reversed to

engage the other threaded portion of the shank and when in this position forming a prolongation of the shank and providing a grip for applying leverage to the shank and the cleaning and polishing element.

5. A cleaning and polishing tool comprising a shank, said shank having screw threads disposed at spaced points thereon, a cleaning and polishing element secured at one end of the shank and projecting substantially at an angle thereto and comprising a single tuft of comparatively rigid bristles, a reversible cap adapted to be selectively engaged with either of said screw threaded portions of said shank to form either a grip for the shank or a housing for said cleaning and polishing element, a dental floss magazine in said shank, and a cap adapted to house the dental floss projecting end, said reversible cap and the last named cap forming a complete housing for the cleaning and polishing tuft and the dental floss projecting end.

In testimony whereof I affix my signature.
